Primary Examiner — Samantha Q Lawrence(74) **Attorney, Agent, or Firm** — Amanda Herman Berghauer(57) **CLAIM**

The ornamental design for an absorbent article as shown and described.

DESCRIPTION

FIG. 1 is a perspective view of an absorbent article showing the front and right sides of the absorbent article, and wherein the grayscale shading indicates contrasting colors from the shaded area versus surrounding areas;

FIG. 2 is a view of the front side of the absorbent article of FIG. 1;

FIG. 3 is a view of the right side of the absorbent article of FIG. 1;

(Continued)

FIG. 4 is a view of the back side of the absorbent article of FIG. 1;
 FIG. 5 is a view of the left side of the absorbent article of FIG. 1;
 FIG. 6 is a view of the top side of the absorbent article of FIG. 1; and,
 FIG. 7 is a view of the bottom side of the absorbent article of FIG. 1.
 The broken lines shown in FIGS. 1-7 illustrate portions of the absorbent article that form no part of the claimed design.
